DAMPER WINDING FOR HIGH SPEED
SALIENT-POLE MACHINES

René A. Baudry, Pittsburgh, Pa., assignor to
Westinghouse Electric & Manufacturing Com-
pany, East Pittsburgh, Pa., a corporation of
Pennsylvania

Application April 14, 1938, Serial No. 201,952

8 Claims. (Cl. 172—120)

My invention relates to dynamo-electric ma-
chines having salient-pole rotor members and
damper windings disposed in the pole-face por-
tions of the salient poles, and it has particular
5 relation to large high-speed machines of that
type.

The particular object of the invention is to
provide new and improved means for taking up
10 the centrifugal forces operating on the end rings
of the damper windings and at the same time
restraining, to a large extent, the distortions due
to the excessive heating when the machine is
being started.

With the foregoing and other objects in view,
15 my invention consists in the combinations, struc-
tures and methods hereinafter described and
claimed, and illustrated in the accompanying
drawing, wherein:

Figure 1 is a fragmentary cross-sectional view
20 of a large synchronous salient-pole machine em-
bodying my invention, parts being broken away
for clarity of illustration, the section-plane be-
ing indicated by the line I—I in Fig. 2.

Fig. 2 is a fragmentary longitudinal sectional
view of the machine, on a somewhat larger scale
25 than Fig. 1, showing one end of the damper
winding, and

Fig. 3 is a fragmentary developed plan view of
a portion of the damper-ring construction with
its associated steadyng ring.

The drawing shows my invention applied, by
way of example, to a large synchronous machine
having a primary-winding stator member 1 of
30 usual construction, and a field-winding rotor
member 2 having twelve salient poles 3, so that
the machine operates at 600 R. P. M. on 60 cy-
cles, which is a fairly high speed for a machine
35 of its size (60,000 kw.), the centrifugal forces de-
veloped in the rotor member being quite high
because of the large diameter, which is practi-
40 cally nine feet.

In the pole-face portions 4 of the salient poles
3 there are disposed damper-winding bars 5, and
45 the bars 5 of each salient pole are joined, at each
of their ends, to a damper segment 6. The twelve
damper segments 6 at each end of the machine
are joined by separate connectors 7, which are
50 shown as comprising two flexible strips which are
bent out of a straight line, as indicated at 8 in
Fig. 3, so that when they expand and contract
due to heating, only a small stress will be pro-
duced in the flexible strips 7.

At each end of the machine, a strong ring 9 is
mechanically associated with the segments 6 and
55 connectors 7, for taking up the centrifugal forces,
and for resisting distortions due to the heating
of the segments and connectors. These parts are
mechanically held together by a large number
60 of bolts 11 which are preferably provided with
spacing washers 12, of relatively poor heat-con-

ductivity, for spacing the ring 9 from the damper
segments 6 and from the connectors 7, so as to
retard the heat-flow to the ring 9.

The damper segments 6, and the separate con-
nectors 7 between the segments, are of copper 5
and are in good electrical connection with each
other, so as to constitute the end-rings for the
damper bars 5, which are also of copper. The
supporting ring 9 is a heavy steel forging made
in one piece, of a grade of steel preferably chosen 10
for its high tensile strength. It has a consider-
ably higher resistivity than copper, so that most
of the damping-current flows through the seg-
ments 6 and connectors 7, rather than through
the rings 9. The spacing washers 12 are pref- 15
erably made of a material having a low-heat
conductivity, such as a nickel-iron alloy, whereby
the heat-transfer to the ring 9 is greatly reduced.
The iron rings 9 could be completely insulated
from the current-carrying parts, but in general 20
I find that the comparative electrical resistivities
are such that practically all of the damper-wind-
ing current is kept out of the ring 9, so that it
is not necessary to attempt to insulate the same.

When a machine of the size illustrated is start-
ed, the starting torque must be supplied by the
damper winding 5, 6 and 7. During the starting
time, which may be of the order of three minutes,
the entire ultimate kinetic energy of the rotor
must be transferred, in the form of heat, to the 30
damper winding. If it were not for heat-radia-
tion, this stored heat would raise all parts of the
damper winding to a temperature of the order
of 900° C. With such heat-radiation as is pres-
ent, the maximum temperature of the damper 35
bars 5 is something of the order of 400° C., which
means a lengthwise expansion of some three-
quarters of an inch in a damper bar 5 of about
eight feet in length. Similar heat effects tend to
cause expansion of the damper segments 6 and 40
end-connectors 7, and these parts can expand
somewhat circumferentially, but the iron ring 9
prevents a movement in the radial direction,
which would communicate itself to the ends of
the damper bars 5 which are brazed to the 45
damper segments 6. I thus prevent the bar-ends
from being bent or distorted to such an extent
that breakage would occur after a certain num-
ber of startings and stoppings of the machine.

According to my invention, the damper seg- 50
ments 6 and the separate connectors 7 are firmly
supported against radial expansion due to ther-
mal and centrifugal forces, which are really
quite high in a machine of this size and speed, by
means of the relatively cool steel ring 9, so that 55
the expansion of the ring 9 is quite low, result-
ing in a corresponding material curtailment of
the possible bending stresses which can be ap-
plied to the ends of the damper bars 5.

While I have described my invention in a form 60

of embodiment which is at present preferred, I wish it to be understood that such embodiment is intended only for illustrative purposes, and not by way of limitation. I desire, therefore, that the appended claims shall be accorded the widest scope of interpretation permitted by the prior art and by the language of the claims.

I claim as my invention.

1. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments comprising connecting-means for preventing an easy direct heat-transfer between the rings and their respective segments.

2. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments and connectors comprising connecting-means for preventing an easy direct heat-transfer between the rings and their respective segments and connectors.

3. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments comprising connecting-bolts between the connected parts, and spacing washers of a relatively poor heat-conductivity associated with said bolts between said connected parts.

4. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments and connectors comprising connecting-bolts between the connected parts, and spacing washers of a relatively poor heat-conductivity associated with said bolts between said rings and said connected parts.

5. A dynamo-electric machine having a salient-pole rotor, damper-winding bars in the pole-face portions of the salient poles, a damper segment for the bars at each end of each salient pole, separate connectors between the several seg-

ments at each end of the machine, a strong ring at each end of the machine for taking up the centrifugal forces and for resisting distortions due to heating of the segments and connectors, and means for mechanically associating the rings with their respective segments comprising connecting-means for preventing an easy direct heat-transfer between the rings and their respective segments, the rings having a higher resistance than the segments and connectors whereby most of the damping-winding current flows through the segments and connectors rather than the rings.

6. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments and connectors comprising connecting-means for preventing an easy direct heat-transfer between the rings and their respective segments and connectors, the rings having a higher resistance than the segments and connectors whereby most of the damping-winding current flows through the segments and connectors rather than the rings.

7. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments comprising connecting-bolts between the connected parts, and spacing washers of a relatively poor heat-conductivity associated with said bolts between said connected parts, the rings having a higher resistance than the segments and connectors whereby most of the damping-winding current flows through the segments and connectors rather than the rings.

8. A dynamo-electric machine having a salient-pole rotor, damper-winding bars in the pole-face portions of the salient poles, a damper segment for the bars at each end of each salient pole, separate connectors between the several segments at each end of the machine, a strong ring at each end of the machine for taking up the centrifugal forces and for resisting distortions due to heating of the segments and connectors, and means for mechanically associating the rings with their respective segments and connectors comprising connecting-bolts between the connected parts, and spacing washers of a relatively poor heat-conductivity associated with said bolts between said rings and said connected parts, the rings having a higher resistance than the segments and connectors whereby most of the damping-winding current flows through the segments and connectors rather than the rings.
